Primary Examiner—Cathron Brooks

(57) **CLAIM**

The ornamental design for an audio/video stand with triple wide frame, as shown and described.

DESCRIPTION

FIG. 1 is a perspective view of an audio/video stand with triple wide frame showing my new design.

FIG. 2 is a front elevational view thereof;

FIG. 3 is a rear elevational view thereof;

FIG. 4 is a right side view thereof, the left side view being a mirror image;

FIG. 5 is a top view thereof; and,

FIG. 6 is a bottom view thereof.
